UNITED STATES PATENT OFFICE.

EDWARD E. JONES, OF WHEELING, WEST VIRGINIA.

BANK-PROTECTING DEVICE.

Application filed December 24, 1926. Serial No. 156,877.

This invention relates to bank protecting devices.

One of its objects is to provide a mechanism comprising bullet-proof plates which 5 may be actuated to enclose the counting room of a bank from the foyer by a bullet-proof wall.

Another object is to provide a device of the character mentioned the plates of which normally serve as shelves or tables on which 10 the ordinary work of the tellers or other bank employees may be carried on.

A still further object is to provide a device of the character mentioned which will be 15 automatically actuated upon any unauthorized attempt being made by a person to enter the counting room of the bank.

Another object of said invention is to provide a device which can be actuated by any 20 employee of the bank from a point remote from the point of danger as well as from a point close thereto.

And a still further object of this invention is to provide a device of the character mentioned 25 none of the parts of which extend underneath the floor, and all parts of which are normally invisible from the foyer, and which normally do not in any way mar the appearance of the partition of a kind commonly used 30 in banks to separate the counting room from the foyer, and which normally do not interfere with, or offer any hindrance to the bank employees in the performance of their customary duties.

And another object is to provide a device 35 of the character mentioned which may be locked in open position, as for cleaning, repairing, and the like, and which may be reset after having been discharged or released, 40 with a minimum expenditure of effort.

With these and other objects in view, the invention resides in the construction and arrangements of parts which will be hereinafter more fully described, reference being had 45 to the accompanying drawings, in which—

Figure 1 is a front elevation of a portion of a partition wall, showing, in dotted lines, the parts of my mechanism which will be visible when in its protecting position;

50 Figure 2 is a rear elevation of a partition wall with which my invention is used, showing the parts thereof in closed, or protecting, position;

Figure 3 is a vertical section on the line 3—3 of Fig. 1; 55

Figure 4 is a vertical section on the line 4—4 of Fig. 1;

Figure 5 is an enlarged fragmentary view of the plate locking and releasing mechanism;

Figure 6 is a rear elevation with parts 60 broken away, showing my mechanism in its open or normal position;

Figure 7 is a horizontal sectional view taken on the line 7—7 of Fig. 6;

Figure 8 is a vertical sectional view taken 65 on the line 8—8 of Fig. 1;

Figure 9 is an enlarged fragmentary view of the spike-bar locking and releasing mechanism;

Figure 10 is a top plan of the mechanism 70 shown in elevation in Fig. 9;

Figure 11 is a front elevation of the hammer mechanism; and

Figure 12 is a vertical section of the same 75 on the line 12—12 of Fig. 11.

In said drawings, the numeral 1 designates the floor line of a banking room, divided into a counting room and a foyer by a partition wall of conventional design generally designated by the numeral 2. Said partition wall 80

comprises a series of conveniently spaced columns 3 supporting a shelf 4 at a convenient height above the floor, with decorative upper mouldings 5, base mouldings 6, and panels 7 therebetween. Mounted upon said 85

shelf as continuations of the posts 3 are upper posts 3^a having a decorative entablature 8 mounted thereto near the upper ends thereof. Mounted upon said entablature in a manner 90

which will be hereinafter described is a moulding 9, and mounted upon said shelf 4 and extending upward to said entablature are opposite posts 10 of a teller's window. Dis- 95

posed between the window posts 10 and the partition posts 3^a are decorative panels 11, preferably made of plate glass. Slidably mounted in the adjacent walls of the window posts 10 is an upper window grating 12 and a lower grating 12' of conventional design.

The portion of said partition located be- 100
tween the median line of the posts 3 constitutes a unit of said partition, and said partition may consist of any desired number of such units. One unit will be herein described, and it will be understood that each unit is 105 identical with that described, except the unit

containing the door, which will be hereinafter particularly described.

Rigidly attached to or formed integral with said entablature 8 near the lower portion thereof and extending horizontally and rearwardly therefrom, is a fin 13. Vertical guide rods 14 are positioned rearwardly of said wall 2, one thereof being located directly behind each of the window posts 10, said rods having their lower ends rigidly fixed to the floor and their upper ends held by said fin 13. Located immediately to the rear of the partition wall 2 and in front of the rods 14 is a bullet-proof plate 15 extending from the floor upward to a point below the level of said shelf 4. Said plate has its upper end bent rearwardly, as at 15^a, to a point beyond the rods 14, and then upwardly, at 15^b. Hinged to the upper end 15^b of said plate 15 and normally extending rearwardly therefrom is a second bullet-proof plate 16 having hinged to the opposite or rearward edge thereof a third bullet-proof plate 17 which is normally held in a substantially horizontal position, as shown in Figs. 3, 4, 5 and 6. Said plate 17 normally serves as a shelf or table on which the duties of the teller are transacted, and normally has its upper surface in the same plane as, and its forward edge flush against, the rearward edge 30 of the shelf 4, as is clearly shown in Figs. 3 and 4. Hinged carried upon said plate 17 at or near its forward edge are sleeves 18. Each of said sleeves is slidably mounted upon one of the rods 14; and disposed around the lower end of each of said rods 14 and extending from said sleeve 18 to a stop block 19 upon or near the floor is a resilient coil spring 20, normally exerting an upward pressure upon said sleeve. Said plates 16 and 17 are normally held in the positions just described in a manner which will be hereinafter described.

Rigidly attached to the plate 15 near its upper edge, as by screws 21, is a series of brackets 22 of suitable size, and a horizontal shaft 23 is journaled in said brackets. Said shaft extends substantially the entire length of the partition wall and has fixed thereto at suitable intervals pawls 24. Said brackets also have pivoted thereto, as at 25, a lever 26 which, in turn, has hinged to its upper end a catch pin 27. Said pin extends through a guideway formed in a block 28 which, in turn, is rigidly mounted upon said bracket 22. Hinged to the plate 17 near its front edge 55 is a bar 29 normally extending downward through an aperture 30 in the plate 15. Said bar is notched at the proper point to receive the forward end of the pin 27. Said pin is normally held in engagement with the notch 60 of said bar by means of a suitable spring 31 disposed between the lower arm of the lever 26 and a block 32 carried by the bracket 22. Said lever 26 has its lower arm disposed opposite the lower end of the pawl 24 so that when said shaft 23 is rotated in a clockwise di-

rection, the pawl 24 will strike against the lower end of the lever 26, thus causing the pin 27 to be withdrawn from the notch of the bar 29 and so allowing the plates 17 and 16 to be by the springs 20 quickly forced upward 70 to and firmly held in closed or protecting position shown in Fig. 2 and in dotted lines in Figs. 1 and 3. The plate 15 has formed therein apertures 33 of suitable dimensions to allow the free passing of the rods 14 75 and springs 20 therethrough. The plate-locking and releasing mechanism just described is preferably located centrally with respect to a unit of the partition wall; that is, directly to the rear of the central portion of the teller's 80 window.

Each of the columns 3 is hollow, and has attached to its inner walls a number of guide blocks 34, 35 and 36. Vertically slideable through said blocks is a bar 37, the upper end 85 of which is received within a yoke 38. A rail 39 carrying on its upper surface a series of upwardly extending, pointed spikes 40, at spaced intervals therealong, has its opposite ends hinged to said yokes 38, and each of said 90 yokes also preferably carries a spike. Said bars and rails are normally held down with the spikes in a concealed position behind the entablature 8 and moulding 9 by means which will hereinafter be described. 95

Each of said bars 37 has fixed thereon at a point intermediate the blocks 35 and 36, a collar 41, and disposed around each of said bars 37 is a resilient coil spring 42 having its lower end resting upon the block 36 and 100 its upper end exerting a lifting pressure on the collar 41.

Attached to each of the columns 3 is a bracket consisting of two arms 43 and 44. The shaft 23 also passes through and is journaled in said bracket, and has fixed thereon a pawl 45 similar in design to the pawl 24. Also mounted within said bracket is a lever 46, pin 47, passing through a guide block 48, and having a spring 49 normally holding 105 said parts in position, this construction being substantially identical with the plate-locking and releasing mechanism hereinbefore described. The forward end of the pin 47 engages a notch 50 formed in the bar 37. Obviously, when said pin is withdrawn from said notch, the pressure of said spring upon the collar 41 will cause said bar 37 to be thrust sharply upward. The upward movement of said bar is arrested by contact of the 110 collar 41 with the lower side of the block 35, and the position of said block, therefore, gauges the extent of upward thrust of said rod, and, consequently, also the spike rails carried thereby. 115

Rotatable disposed upon said shaft 23 in embracing relation to the pawl 45 is a hammer 51. Said hammer has its forward face rabbeted, as at 51^a, as shown in Figs. 11 and 12, to receive therein the upper portion 120 125

130

of said pawl 45. Attached to said hammer, as by screws 52, are the upper ends of two leaf springs 53 and 54. Each of said springs has its lower end hooked, as at 53^a and 54^a, respectively, to receive one end of a link, as 55, and a hook 56 suitably positioned upon the lower part of the column 3, receives the other end of said link when the mechanism of my invention is cocked, or ready to be tripped or sprung. A lever 57 is pivoted near its middle, as by means of the pin 58, to the bracket 43. Said lever has its rear end formed to form arms 57^a and 57^b, and hinged to each of said arms near its end is the upper end of a thrust rod 59. The lower end of said thrust rod is hinged to one end of a treadle lever 60, which, in turn, is pivoted to a floor bracket 61. Received within a socket 60^a formed on said lever 60 is one end of a treadle bar 62 which has its opposite end received within the socket of a corresponding lever.

Formed upon the lower side of the lever 57 intermediate its fulcrum point and its rear end, is a tooth 63 designed to engage a shoulder 64 formed on the upper end of the hammer 51. Said tooth and shoulder must be in engagement when the mechanism is set, or cocked, and the tension of the leaf springs 53 and 54 normally hold the shoulder of said hammer tightly against said tooth 63.

Thus it will be seen that downward pressure exerted upon the treadle bar 62 will cause the tooth 63 to be lifted free from engagement with the shoulder 64 of the hammer 51, whereupon the tension of the springs 53 and 54 will cause said hammer forcefully to strike against the pawl 45, thus rotating the shaft 23, and causing the pawl 45 to strike the lever 46, withdrawing the pin 47 from the notch in the bar 37, and allowing said bar to be thrust upward in a manner hereinbefore described. At the same time, the sharp rotation of said shaft 23 in the manner just described, will also release the plate-elevating mechanism hereinbefore described.

It will be understood that, while there are a number of hammers and complementary mechanisms disposed at intervals throughout the length of the partition wall, preferably one behind each of the columns 3, any one of these hammers may be released independently of all the others, the intent being to have any one of the springs 53 or 54 of sufficient strength to release the mechanism throughout its entire length.

In order to prevent accidental discharge of my mechanism at a time when its protection is not needed, or for cleaning, repairing, and the like, a locking device is provided comprising a horizontal shaft 65 extending through and journaled in the brackets 22, 43 and 44, having cams 66 fixed thereon at points preferably located almost directly above the toothed portion of each of said levers 57.

Said cam is shown in locking position in Figs. 8 and 9, and in the latter figure said cam is shown in dotted lines in its open or "ready" position. In order to facilitate the operation of said cam, at convenient intervals along said shaft 65 are provided laterally extending arms 67. Said arms are rigidly fixed to said shaft, and are jointed, as at 68, to allow of movement of their outer ends toward said shaft. Said arms are so fixed to said shaft that when said arms are hanging vertically downward, said cams 66 occupy the position shown in dotted lines in Fig. 9, and when said arms are raised to a horizontal position, said cams are thereby rotated to the locking position shown in full lines in Figs. 8 and 9. For holding said arms horizontally, conveniently placed rests 69 are provided, as upon the sides of a cabinet 70. The joint in said arms permit their clearing said rest when being raised thereto or lowered therefrom. Manifestly, when said cams are in locking position, discharge of the releasing mechanisms heretofore described is thereby prevented.

The cabinet just referred to may be of any desired design, but preferably has a drawer or other receptacle near the top thereof suitable for receiving a revolver, and so constructed that elevation of the plates 16 and 17 will expose said revolver and make it easily accessible to the teller. And if desired, a port hole 71 may be provided in the plate 16 to allow of shooting therethrough by the teller.

In case said porthole is provided, then the upper window grating 12 should be raised to obviate interference of said grating with bullets aimed through said port hole. This is done by extending lugs 72 through a guide-way (not shown) in the window casing, designed to engage with the sleeves 18 as said sleeves travel upward along the rods 14.

Pivoted to the upper end of said window grating, at each side thereof, is a trigger 73 having a tooth 73^a normally engaged in underlying relation to a lever 74. Said lever is pivoted intermediate its ends to a bracket 75 fixed upon the fin 13, and hinged to the opposite end of said lever is the upper end of a thrust rod 76 which has its lower end received by a yoke 77 partially surrounding the bar 37. Another rod 78 extends downward from said yoke 77 to the forward end of the lever 57. A resilient coil spring 79 surrounding the upper portion of said rod 78 and extending from the upper side of the block 34 to the bottom of said yoke 77 normally prevents the exertion of pressure upon the lever 57.

Thus it will be readily understood that an unauthorized raising of the upper window grating will, through the mechanism just described, release the hammers, and, consequently, the entire protective structure.

Also carried by the upper window grating

12 at a point where they will be engaged by the lower grating 12' when the latter is raised beyond a certain height, are lugs 80. From this it will be seen that an attempt to raise 5 the lower window grating beyond the height of the lugs 80 will also release the mechanism of my invention.

In order to facilitate repositioning of the mechanism just described after it has been 10 released, the lugs 72 of the trigger 73 have their lower edges beveled to permit said lugs to slide downward over the adjacent ends of the levers 74. A resilient coil spring 81 disposed between the topmost frame of the 15 window grating 12 and a shoulder 82 formed on the trigger 73 opposite the lug 72, normally holds said lug in engagement with the adjacent end of the lever 74, and permits sufficient movement of said trigger away from 20 said lever 74 in the act of repositioning as to allow said lug to slide or jump over the end of said lever.

In order that any attempt of a bandit or other person to enter the counting room by 25 scaling the partition wall and passing over the top thereof may be frustrated, or, at least rendered more difficult, and at the same time to release my protective mechanism, I prefer to have the moulding 9 slotted underneath, as 30 shown at 83 in Figs. 3 and 4, to receive therein the upper edge of and to be slidably downward upon, the entablature 8. And having their upper ends fastened to, and extending downward from said moulding are thrust 35 rods 84, as shown most clearly in Fig. 8. The lower ends of said rods are received within the yoke 77. Thus it will be seen that downward pressure exerted upon the moulding 9 will, by means of the mechanism just 40 described, release one or more of the hammers 51 and so discharge or release the entire mechanism of my invention.

Corners in the partition may, of course, be turned by using beveled gear wheels on the 45 shafts in a manner well understood in the art.

It will be readily understood that when the mechanism of my invention is set or cocked in the ready position, none of the 50 working parts thereof will be visible to a person standing in front of the partition wall thereof, or elsewhere in the foyer of the banking room.

It will also be apparent that the releasing 55 mechanism of my invention may be tripped by a bank employee by exerting downward pressure upon the treadle bar, and that said mechanism will also be automatically released when an attempt is made to enter the counting room either by raising the window grating, or by scaling the partition and climbing over the top thereof.

In order to cock or reset the mechanism of 60 my invention after the same has been released or discharged, first, the hooked lower

ends of the springs 53 and 54 are removed from their links 55, allowing said springs to assume positions substantially as shown in dotted lines in Fig. 8. Next, each of the hammers throughout the length of the shaft 70 23 is reset by placing the tooth 63 of the lever 57 in engagement with the shoulder 64 of said hammer, and locking the same in place by rotating the cam shaft 65 to carry the cam 66 into locking relation with respect 75 to said lever, as shown in full lines in Fig. 9. Each of the plates 17 may then be lowered to normal position by means of manual pressure directed rearwardly against the forward face of said plate or its complementary 80 plate 16, and then downward manual pressure upon the upper surface of the plate 17 near its forward edge. When said plates are pressed downward to the proper position, the pin 27 is placed in engagement with the 85 notch in bar 29 in a manner which will be readily understood, for holding said plates in lowered position. The window gratings are actuated by gravity to slide into normal 90 position when said plates are lowered, and the moulding 9 is, through its associated mechanism, automatically repositioned by setting the lever 57 in a manner which will be readily understood. Each of the bars 37 may then be lowered to normal position by 95 means of manual pressure directed downwardly thereon, and the catch pin 47 placed in engagement with the notch 50 in each of said bars. Then the springs 53 and 54 are hooked to the links 55, and as a last step the cam shaft 65 is rotated to carry the cams 66 to the raised or open position illustrated in dotted lines in Fig. 9, whereupon my mechanism is set or cocked, or in the "ready" position. 100

I claim—

1. A banking fixture comprising a partition wall separating the banking room into a foyer and a counting room, a substantially vertical bullet-proof plate disposed to the rear of said wall and extending upward from the floor substantially to counter height, a second bullet-proof plate hinged to said first plate and normally extending rearwardly therefrom, a third bullet-proof plate hinged to said second plate and normally extending forwardly therefrom, and means for raising said second and third plates into a substantially vertical position above said first plate. 110

2. A banking fixture comprising a partition wall separating the banking room into a foyer and a counting room, a substantially vertical bullet-proof plate disposed to the rear of said wall and extending upward from the floor substantially to counter height, a second bullet-proof plate hinged to said first plate and normally extending rearwardly therefrom, a third bullet-proof plate hinged to said second plate and normally extending forwardly therefrom, said second and third 115 120 125 130

plates when in normal or open position constituting a counter for the use of a banking teller, and means for raising said second and third plates into a substantially vertical position above said first plate.

3. A banking fixture comprising a partition wall separating the banking room into a foyer and a counting room, a substantially vertical bullet-proof plate disposed to the rear of said wall and extending upward from the floor substantially to counter height, a second bullet-proof plate hinged to said first plate and normally extending rearwardly therefrom, a third bullet-proof plate hinged to said second plate and normally extending forwardly therefrom, and means for raising said second and third plates into a substantially vertical position above said first plate, said three plates when so elevated constituting a bullet-proof wall extending from the floor of the banking room upward substantially to the top of said partition.

4. A banking fixture comprising a partition wall separating the banking room into a foyer and a counting room, a substantially vertical bullet-proof plate extending upward from the floor of the banking room behind and contiguous to said wall substantially to counter height, a second bullet-proof plate hinged to said first plate at or near its upper edge and normally extending rearwardly therefrom, a third bullet-proof plate hinged to said second plate at or near its upper edge and normally extending forwardly therefrom, and means for elevating said second and third plates to and holding the same in substantially vertical positions to constitute a bullet-proof wall extending from the floor of the banking room upward substantially to the top of said partition.

5. A banking fixture comprising a partition wall separating the banking room into a foyer and a counting room, a substantially vertical bullet-proof plate extending upward from the floor of the banking room behind and contiguous to said wall substantially to counter height, a second bullet-proof plate having its forward edge hinged to said first plate near the top thereof and normally extending rearwardly therefrom, a third bullet-proof plate hinged to said second plate near its rear edge and normally extending forwardly from said hinge in a substantially horizontal position, and means connected to the forward end of said third plate for moving said second and third plates to and holding the same in a substantially vertical position.

6. A banking fixture comprising a partition wall separating the banking room into a foyer and a counting room, a substantially vertical bullet-proof plate extending upward from the floor of the banking room behind and contiguous to said wall substantially to counter height, a second bullet-proof plate having its forward edge hinged to said

first plate near the top thereof and normally extending rearwardly therefrom, a third bullet-proof plate hinged to said second plate near its rear edge and normally extending forwardly from said hinge in a substantially horizontal position, and means connected to the forward end of said third plate for moving said second and third plates to and holding the same in a substantially vertical position, said means comprising sleeves slidably mounted upon vertical bars.

7. A banking fixture comprising a partition wall separating the banking room into a foyer and a counting room, a substantially vertical bullet-proof plate extending upward from the floor of the banking room behind and contiguous to said wall substantially to counter height, a second bullet-proof plate having its forward edge hinged to said first plate near the top thereof and normally extending rearwardly therefrom, a third bullet-proof plate hinged to said second plate near its rear edge and normally extending forwardly from said hinge in a substantially horizontal position, means connected to the forward edge of said third plate for moving said second and third plates to and holding the same in a substantially vertical position, means normally holding said second and third plates in lowered position, and tripping means for releasing said plate-holding means.

8. A banking fixture comprising a partition wall separating the banking room into a foyer and a counting room, a substantially vertical bullet-proof plate extending upward from the floor of the banking room behind and contiguous to said wall substantially to counter height, a second bullet-proof plate having its forward edge hinged to said first plate near the top thereof and normally extending rearwardly therefrom, a third bullet-proof plate hinged to said second plate near its rear edge and normally extending forwardly from said hinge in a substantially horizontal position, means connected to the forward edge of said third plate for moving said second and third plates to and holding the same in a substantially vertical position, means normally holding said second and third plates in lowered position, tripping means for releasing said plate-holding means, a movable moulding mounted upon said partition, and means associated with said moulding for actuating said tripping means.

9. A banking fixture comprising a partition wall separating the banking room into a foyer and a counting room, a substantially vertically vertical bullet-proof plate extending upward from the floor of the banking room behind and contiguous to said wall, a second bullet-proof plate having its forward edge hinged to said first plate near the top thereof and normally extending rearwardly therefrom, a third bullet-proof plate hinged

- to said second plate near its rear edge and normally extending forwardly from said hinge in a substantially horizontal position, means connected to the forward edge of said 5 third plate for moving said second and third plates to and holding the same in a substantially vertical position, means normally holding said second and third plates in lowered position, tripping means for releasing said 10 plate-holding means, a window formed in said partition wall above said first plate, a grating slidable vertically within the posts of said window, and means associated with said plate-raising means and said grating whereby 15 the latter is raised by said plate-elevating means.
10. A banking fixture comprising a partition wall separating the banking room into a foyer and a counting room, a substantially 20 vertical bullet-proof plate extending upward from the floor of the banking room behind and contiguous to said wall, a second bullet-proof plate having its forward edge hinged to said first plate near the top thereof and 25 normally extending rearwardly therefrom, a third bullet-proof plate hinged to said second plate near its rear edge and normally extending forwardly from said hinge in a substantially horizontal position, means connected
- to the forward edge of said third plate for 30 moving said second and third plates to and holding the same in a substantially vertical position, a moulding mounted upon said partition, and means associated with said moulding whereby downward pressure upon the 35 latter will cause said plate-moving means to move said plates to closing or vertical position.
11. A plurality of foldable elements, means normally holding said elements folded, and 40 means for extending said elements, said last-mentioned means comprising a guide rod, a block fixed to one end of said rod, a sleeve 45 slidable upon said rod, and a coil spring encircling said rod intermediate said block and said sleeve so as to exert pressure against the latter.
12. A plurality of foldable elements, means normally holding said elements folded, 50 means for extending said elements, said last-mentioned means comprising a guide rod, a block fixed to one end of said rod, a sleeve 55 slidable upon said rod, and a coil spring encircling said rod intermediate said block and said sleeve so as to exert pressure against the latter, and means for releasing said holding means.

EDWARD E. JONES.
